-18. OR D 20,206 EX

DESIGN.

—
H. C. ARMSTRONG.
WAGON BODY.

No. 20,206.

Patented Oct. 14, 1890.

UNITED STATES PATENT OFFICE.

HENRY C. ARMSTRONG, OF PROVIDENCE, RHODE ISLAND.

DESIGN FOR A WAGON-BODY.

SPECIFICATION forming part of Design No. 20,206, dated October 14, 1890.

Application filed September 22, 1890. Serial No. 366,831. Term of patent 14 years.

To all whom it may concern:

Be it known that I, HENRY C. ARMSTRONG, a citizen of the United States, residing at Providence, in the county of Providence and State of Rhode Island, have invented and produced a new and original Design for a Wagon-Body; and I hereby declare that the following is a full, clear, and exact description of the same, reference being had to the accompanying photographic view, forming part of this specification.

This design relates to the main body of the wagon back of the driver's seat.

The photographic view shows the wagon in perspective.

The leading feature of my design consists in the outlines and configuration of a bass-drum, forming the main body of the wagon.

A is the main body of the wagon. It is in the form of a cylinder placed with the axis

transversely to the length of the wagon, the closed circular ends forming the sides of the wagon-body.

B is the driver's seat, covered by the cab C.

The cylinder is ornamented with the diagonal lines D. The general appearance resembles a bass-drum.

Having thus described my design, I claim as new and desire to secure by Letters Patent—

The design for the body of a wagon, herein shown and described, the same comprising the cylindrical body A, the lines D on the surface of the cylinder, and the seat B, extending forward from the cylindrical body, as set forth.

HENRY C. ARMSTRONG.
